US00D858769S

(12) **United States Design Patent** (10) Patent No.: **US D858,769 S**
(45) Date of Patent: ** Sep. 3, 2019

(54) **INTERVERTEBRAL IMPLANT**(71) Applicant: **NuVasive, Inc.**, San Diego, CA (US)(72) Inventors: **Michael Barela**, San Diego, CA (US);
Chad Grant, Escondido, CA (US)(73) Assignee: **NuVasive, Inc.**, San Diego, CA (US)(***) Term: **15 Years**(21) Appl. No.: **29/596,083**(22) Filed: **Mar. 6, 2017****Related U.S. Application Data**

(63) Continuation of application No. 29/509,736, filed on Nov. 20, 2014, now abandoned.

(51) **LOC (12) Cl.** ..... **24-03**(52) **U.S. Cl.**USPC ..... **D24/155**(58) **Field of Classification Search**USPC ..... **D24/155**CPC A61F 2/4611; A61F 2/442; A61F 2/447;

CLAIM

The ornamental design for an intervertebral implant, substantially as shown and described.

DESCRIPTION

FIG. 1 is a perspective view of an intervertebral implant showing our new design;
FIG. 2 is a top view of the intervertebral implant of FIG. 1;
FIG. 3 is a side view of the intervertebral implant of FIG. 1;
FIG. 4 is a front view of the intervertebral implant of FIG. 1;
FIG. 5 is a back view of the intervertebral implant of FIG. 1;
FIG. 6 is a perspective view of a first alternative embodiment of an intervertebral implant;
FIG. 7 is a top view of the intervertebral implant of FIG. 6;
FIG. 8 is a side view of the intervertebral implant of FIG. 6;
FIG. 9 is a front view of the intervertebral implant of FIG. 6;
FIG. 10 is a back view of the intervertebral implant of FIG. 6;
FIG. 11 is a perspective view of a second alternative embodiment of an intervertebral implant;
FIG. 12 is a top view of the intervertebral implant of FIG. 11;
FIG. 13 is a side view of the intervertebral implant of FIG. 11;
FIG. 14 is a front view of the intervertebral implant of FIG. 11;
FIG. 15 is a back view of the intervertebral implant of FIG. 11;
FIG. 16 is a perspective view of a third alternative embodiment of an intervertebral implant;
FIG. 17 is a top side view of the intervertebral implant of FIG. 16;
FIG. 18 is a side view of the intervertebral implant of FIG. 16;
FIG. 19 is a front view of the intervertebral implant of FIG. 16;
FIG. 20 is a back view of the intervertebral implant of FIG. 16;
FIG. 21 is a perspective view of a fourth alternative embodiment of an intervertebral implant;
FIG. 22 is a top side view of the intervertebral implant of FIG. 21;
FIG. 23 is a side view of the intervertebral implant of FIG. 21;

FIG. 24 is a front view of the intervertebral implant of FIG. 21;
FIG. 25 is a back view of the intervertebral implant of FIG. 21;

FIG. 26 is a perspective view of a fifth alternative embodiment of an intervertebral implant;
FIG. 27 is a top side view of the intervertebral implant of FIG. 26;

FIG. 28 is a side view of the intervertebral implant of FIG. 26;
FIG. 29 is a front view of the intervertebral implant of FIG. 26;

FIG. 30 is a back view of the intervertebral implant of FIG. 26;
FIG. 31 is a perspective view of a sixth alternative embodiment of an intervertebral implant;

FIG. 32 is a top side view of the intervertebral implant of FIG. 31;

FIG. 33 is a side view of the intervertebral implant of FIG. 31;
FIG. 34 is a front view of the intervertebral implant of FIG. 31;

FIG. 35 is a back view of the intervertebral implant of FIG. 31;
FIG. 36 is a perspective view of a seventh alternative embodiment of an intervertebral implant;

FIG. 37 is a top side view of the intervertebral implant of FIG. 36;

FIG. 38 is a side view of the intervertebral implant of FIG. 36;

FIG. 39 is a front view of the intervertebral implant of FIG. 36;

FIG. 40 is a back view of the intervertebral implant of FIG. 36;

FIG. 41 is a perspective view of an eighth alternative embodiment of an intervertebral implant;

FIG. 42 is a top side view of the intervertebral implant of FIG. 41;

FIG. 43 is a side view of the intervertebral implant of FIG. 41;

FIG. 44 is a front view of the intervertebral implant of FIG. 41; and,

FIG. 45 is a back view of the intervertebral implant of FIG. 41.

The broken line showing is included for the purpose of illustrating environment and forms no part of the claimed design.
